UNITED STATES PATENT OFFICE.

FREDERICK E. PLACE, OF CHICAGO, AND MERRILL L. JENKINS, OF HARVEY, ILLINOIS,
ASSIGNORS TO THE BUDA COMPANY, OF CHICAGO, ILLINOIS, A CORPORATION OF
ILLINOIS.

DRILLING APPARATUS.

1,175,556.

Specification of Letters Patent. Patented Mar. 14, 1916.

Application filed October 24, 1911. Serial No. 656,426.

To all whom it may concern:

Be it known that we, FREDERICK E. PLACE and MERRILL L. JENKINS, citizens of the United States, and residents, respectively, 5 of Chicago and of Harvey, both in the county of Cook and State of Illinois, have invented certain new and useful Improvements in Drilling Apparatus, of which the following is a specification.

10 Our present invention relates to drilling apparatus in general, and more particularly to portable apparatus of this character and has special reference to the provision of an improved form of drilling apparatus pecu- 15 liarily available for operations upon unwieldy objects such as railroad rails which are not conveniently movable.

The principal objects of our present invention are the provision of improved means 20 for engaging the apparatus with the rail or other work to be operated upon whereby it is firmly held against movement relatively thereto and may be adapted to accommodate work of different sizes; the provision of im- 25 proved clamping means for maintaining such engagement; the provision of improved means for facilitating the ready disengagement of the apparatus from the work; the provision of an improved con- 30 struction whereby the drilling machine proper may be demounted from the frame or carriage by means of which it is supported in operative relation to its work; the provision of improved construction and ar- 35 rangement of the frame drill for supporting them close to the work in operative relation thereto, whereby a most rigid structure is attained; the provision of an im- 40 proved unitary form of frame construction whereby disadvantages ensuing upon parts working loose or the structure becoming racked out of shape are avoided; the pro- 45 vision of an improved construction whereby the thrust of the drill is received by the frame directly instead of through connec- 50 tions, thereby avoiding all resiliency tending to break the drill as it springs through the material upon which it is operating; the provision of an improved form of driv- 55 ing mechanism for the drill, whereby the driving and feeding elements are at all times held in alinement, wherein the driving and feeding elements may be simultaneously adjusted in an extremely simple manner, and wherein the adjustment of one of the

members relative to the other may likewise be accomplished in an extremely simple manner; and generally to provide an apparatus of the character described of great efficiency, strength and simplicity and of low cost of manufacture and maintenance, together with such further and additional objects as may hereinafter appear.

In the attainment of the foregoing objects, as well as certain advantages to be 65 below more fully disclosed, we have provided a construction one embodiment of which is illustrated in the accompanying drawings, wherein—

Figure 1 is a side elevational view, partly 70 in section, showing our improved apparatus, for purposes of illustration, in engagement with a railway rail; Fig. 2 is a rear elevational view and Fig. 3 is a plan view of the apparatus of Fig. 1; Fig. 3^a is a fragmentary side elevation of the rear portion of the drilling machine adjacent the ground; Fig. 3^b is a fragmentary vertical section on the line 3^b—3^b of Fig. 3^a. Fig. 4 is an elevational view of a part of the apparatus 75 viewed from a position opposite to that shown in Fig. 1; Fig. 5 is an enlarged view of a detail of construction shown in Fig. 2; Fig. 6 is a sectional view taken on the line VI—VI of Fig. 1; and Fig. 7 is a sectional view of a detail of construction taken on the line VII—VII of Fig. 3. Fig. 7^a is a perspective view of a detail of construction.

Referring first more particularly to Figs. 1 and 3 of the drawings, it will be observed 90 that in embodying our invention in a machine specially adapted for the drilling of railway rails, in which field it is of great utility, though nevertheless available for many other applications, we provide a construction wherein we utilize two relatively 95 movable frames.

For supporting the apparatus as a whole we employ a main substantially horizontal frame including as here shown the preferably parallel members 10—10' attached at their rear ends to the supporting stand 11 which has a rearward extension 12, in order to provide a firm base for one end of the machine, the opposite ends of the members 10—10' being maintained in spaced relation by a distance rod 13 and turned downwardly in order to provide tension hooks 14—14 to engage one side of the head 15 of a rail 16, in order that the drill may be in 110

position to operate upon the web 17 of the rail. To the end that the device just described, in combination with the thrust member to be described below, may most effectively engage rail heads of different sizes, each of the hooks 14 is provided with a take up screw 18 having a lock nut 19.

For supporting the drill stock and the driving and feeding mechanism therefor, and the thrust and clamping member co-operating with the hooks 14, we employ a vertical frame comprising the members 20 and 21-21' (see Fig. 2) connected longitudinally adjacent the top as indicated at 22 and adjacent the bottom as indicated at 23-23', and transversely as indicated at 24-24', this frame including the members 20, 21-21', 22, 23-23' and 24-24', being desirably cast in the form of a unitary structure in order to secure the greatest possible degree of rigidity.

For slidably supporting the rear end of the vertical frame, the members 21-21' are provided adjacent their lower edges with 25 shoes 25, 26 riding upon the upper surface of extensions 27-28 of the frame members 23-23', the said members 21-21' also being provided with shoes 29-30 adapted to ride on the under surfaces of such extensions to prevent the frame from tilting forwardly, and for slidably supporting the opposite end of the frame and as engaging means co-operating with the hooks 14, we provide on the member 20 a forwardly extending thrust member, 31, here shown as of a skeleton construction including the legs 32, 33 and 34 suitably fastened to the said member 20 as by bolts 35-35, and provided with a cross head 36 having shoes 37-37 riding upon lateral extensions 38-38 of the members 10-10' and co-operating shoes 39 engaging the lower surface of such projection. For contacting with the rail and holding it firmly against the hooks 14, the thrust member is provided with an enlarged abutment surface 40 preferably centralized on the cross-head 36 so as to be sustained against bending, by means of the radially disposed members 32, 33, 34 and 36.

For moving the vertical frame forwardly and thereby causing the abutment surface 40 of the thrust-member to approach the plane of the hooks 14 and engage the rail head, we employ a bifurcated operating lever 41, whose ends, by extensions 42, and 43, are mounted upon pivot pins 44, 45 between ears 46-46 and 47-47 formed on the frame members 10-10' (see Figs. 2 and 3). Such lever 41 is pivotally engaged at 48 to a toggle link 49 which is in turn pivoted at 50 to an extension 51 of the frame member 21', as will be seen on viewing Figs. 3 and 4. The position assumed by the lever 41 and link 49 when the rail is engaged is shown in full lines in Fig. 4, while the po-

sition assumed thereby when the rail holding members are separated is indicated in dotted lines in such figure. When it is desired, however, to separate the frames, for purposes of repair or otherwise, the nuts 70 48, 50, etc., may be removed so that the links they hold in place can be readily separated to allow the frame which carries the drill to be moved rearwardly as a whole away from its supporting side frame 10.

To prevent any accidental rearward movement of the vertical frame, the lever 41 is provided with wedge blocks 52 and 54, which, when such lever is moved into the position shown in Fig. 1, engage between 80 the shoes 25 and 26 and the abutments 53 and 55 and co-operate with the toggle link. The wedge blocks 52 and 54 are conveniently similitudes and preferably inclined to co-operate with the inclined surfaces of 85 the abutments 53 and 55 as indicated in Figs. 3^a and 4.

Referring now more particularly to Figs. 1, 2 and 4, it will be apparent that to the end that the drill stock 56 may be rotated it is splined in a bushing 57 rotatably carried in an enlargement 58 of the transverse frame members 24. In order that it may be susceptible of longitudinal movement as well as rotation, the drill stock 56 is provided with a longitudinal slot 59 which forms a key way for a spline 60 engaging said slot and likewise said bushing 57. For moving the stock 56 and feeding the bit 61 carried thereby into the work, the stock is screw threaded, as indicated at 62, and mounted in a nut 63 carried in an enlarged portion 64 of the transverse frame member 21'. This enlarged portion 64, together with the washer 65 and the collar 66 and lock nut 67 comprise a housing for a ball race 68, thus constituting an anti-friction bearing for said nut. For protecting the thread 62 a sleeve 69, loosely carried on the drill stock 56, is employed intermediate the parallel frame members 20 and 21, and the portion of the thread on the rearwardly projecting end of the stock is covered by a sleeve 69', having threaded engagement with the nut 63 as shown in Fig. 1.

For driving the drill stock 56 we employ a sprocket 70 fixed on the bushing 57 and connected by a chain 71 to a sprocket wheel 72 rotatably mounted on a crank shaft 73, and for feeding the drill stock 56 we employ a pinion 74 fixed on the nut 63 and connected by a chain 75 to a sprocket 76 mounted on said shaft 73 and fixed against rotation thereon. For protecting the pinion 70 we form on the transverse member 24 a shield 70' which is sufficiently extended to form a leg for the support of the machine.

On inspection of Fig. 5 it will be apparent that for moving the idler roller 77 and thereby varying the tension on the chain

75, we provide intermediate the vertical frame members 21—21' a transverse member 78 slotted as indicated at 79 to receive the pintle 80 carrying a bushing 80' upon which said idler 77 rotates, said bushing having a collar bearing against the frame and said pintle being partially screw threaded and provided with a nut 81 bearing on said bushing, whereby the pintle may be held fixedly in predetermined position.

As will be clearly manifest on viewing Fig. 6, for moving both of the sprockets 72 and 76 simultaneously relative to the drill stock 56, in a plane parallel thereto and at all times maintaining their alinement, the shaft 73 is revolvably mounted in an eccentric bearing 82 which in turn is rotatably mounted in split extensions 83—84 of the frame members 20 and 21, which form journals for said eccentric bearing, each of said members 83, 84 being provided with extended ears 85—86, 85—86, the eccentric being held in predetermined position by means of the cap screws 88 and 89.

For driving the crank shaft 73 and operating the drill, a crank or handle 90 is provided, at the rear of the machine, and, as means for inducing simultaneous rotation and feed of the drill stock, we mount at the front of the machine, on the shaft 73, a hollow arm 91 having pivoted thereto a bifurcated dog 92' (see Fig. 7^a) adapted to engage one of the spider legs 93 of the sprocket 72, such dog being provided with an operating finger 94 whereby it may be readily moved into or out of position. For normally holding said dog in adjusted position, we employ a plunger, 95, carrying a collar 96, said plunger having one of its ends 97 passing through an extension 98 arranged within said arm 91 and the other of its ends 99 reciprocally mounted in a guide 100, a spring 101 encircling said plunger and sustaining it in contact with the dog 92.

From the foregoing description it will be seen that in the operation of drilling apparatus embodying our invention, when the drill stock 56 is moved to the extreme right, opposite to its position shown in Fig. 1, and the operating lever 41 likewise thrown to the extreme right, the machine may be placed in position with the frame members 10 resting upon the rail head, so that the hooks 14 will bear against one side of such head. The lever 41 being then moved to the left so that it will occupy substantially the position shown in Fig. 1, the entire vertical frame will likewise be moved to the left forcing the abutting surface 40 of the thrust member against the side of the rail-head opposite the hooks 14, and the take up screws 18 being properly placed to accommodate the rail, the rail is firmly clamped in position between the fixed abutments formed by the hooks 14

and the movable abutment formed by the thrust member 31. The finger 94 being depressed from the position shown in Fig. 1, the operating handle 90 being revolved clockwise (viewed from the rear) the drill stock 56 is rapidly fed forward without rotation until the bit 61 strikes the web 17. The finger 94 being then moved to the position shown in Fig. 1, the sprocket 72 being thereby held against rotation on the shaft 73, the drill stock 56 will then be rapidly rotated through the rotation of the sprocket 70, as well as fed forwardly by the rotation of the nut 63 through the pinion 74. Inasmuch as both the horizontal frame members and vertical frame members are in rigid engagement with the rail head 15, transmitting the thrust of the drill directly to the frame, there will be no spring tending to fracture the drill bit as it breaks through the rail web 17. It will be further observed that inasmuch as the vertical frame is conveniently made in one piece, properly trussed and braced, there are no relatively movable parts which can work loose or become racked out of position; that since the movement of the lever into position shown in Fig. 1 clamps the rail firmly into the machine before the drilling operation is started, the rail is held in such clamped position by virtue of the arrangement of the wedge blocks heretofore described, the rail will be held in such clamped position until the lever is moved out of position shown in Fig. 1; that by reason of their long angle of bend and 95 their support upon and close up to the rail, by means of the cross head 36, the rail hooks are most rigid and avoid the tendency to bend present in the common construction of curved hooks. It will further be noted that by virtue of the employment of the sleeves 69 and 69', and the shield 70' the threaded portion of the drill stock, and the sprocket 70, are well protected from the entrance of 100 foreign matter; that by reason of the simple construction of idler roller support, any slack in the feed chain 75 may be taken up by movement of a single screw; and that by means of the mounting of the sprocket 72 and 76 on the shaft 73 carried in the eccentric 105 82, not only are the sprockets always held in alinement, but by simply loosening the two cap screws 88 and 89, then turning the eccentrics, and finally tightening the two screws, both chains may be simultaneously tightened or loosened without disturbing their alinement.

Other advantages of machines embodying our invention will be apparent to those who are skilled in the art to which it pertains.

Having thus described our invention and illustrated its use, what we claim as new and desire to secure by Letters Patent is the following:

1. In a rail drilling apparatus, in combi-

nation, a pair of frames slidable on and relatively to each other, toggle means for locking said frames against relative movement, rail holding abutments on each frame, and 5 means for varying the distance one set of abutments projects from the frame which supports them, whereby the distance between opposing abutments when the frames are in locked position may be adjusted.

10 2. In a rail drilling apparatus, in combination, a stationary frame having a tension member, a second frame slidable on and relatively thereto and having a thrust member, toggle means for locking said frames 15 against relative movement, rail holding abutments on each frame, means for varying the distance one set of abutments project from the frame which supports them, whereby the distance between opposing 20 abutments when the frames are in locked position may be adjusted.

3. In a rail drilling apparatus, in combination, a frame provided with a pair of tension hooks, a second frame slidable on and 25 relatively thereto and having a fixed thrust member, toggle means for locking said frames against relative movement, rail holding abutments on each frame, and means for varying the distance one set of abutments 30 projects from the frame which supports them, whereby the distance between opposing abutments when the frames are in locked position may be adjusted.

4. In a rail drilling apparatus, in combination, a pair of frames slidable on and relatively to each other, toggle means for locking said frames against relative movement, rail holding abutments on each frame, the abutments on one frame being provided 40 with take-up means, whereby the distance between opposing abutments when the frames are in locked position may be adjusted.

5. In a rail drilling apparatus, in combination, a pair of frames slidable on and relatively to each other, each provided with rail holding abutments, means for varying the distance one set of abutments projects from the frame which supports them, and toggle 50 means for sliding said frames relatively to each other.

6. In a rail drilling apparatus, in combination, a pair of relatively movable frames provided with co-acting pairs of abutments, 55 and means for moving one of said frames provided with means adapted to be interposed between the members of one pair of said abutments upon movement thereof, whereby the frame is held in moved position, the opposite pair of said abutments being adapted to coact with the other pair of said abutments for simultaneously gripping a rail therebetween.

7. In a rail drilling apparatus, in combination, a pair of relatively movable frame

members provided with rail holding abutments, one of said frame members being provided with a cross head engaging the other of said frame members whereby said abutments are mutually supported and 70 means for holding the abutments in adjusted position.

8. In a rail drilling apparatus, in combination, a pair of relatively movable frame members provided with rail holding abutments, a drill carried by one of said frame members, driving mechanism for said drill carried by said last-mentioned frame member, said drill being movable axially relatively to said frame and said driving mechanism, and means for moving said last-mentioned frame member relatively to the other frame member, whereby the abutment carried by the first-mentioned frame member and the drill is caused to approach the other 85 of said abutments.

9. In a rail drilling apparatus, in combination, a frame member provided with a pair of tension hooks, a frame member provided with a thrust bar and a cross head, 90 and means whereby said frame members may be moved relatively to each other, said cross head being constructed to engage with said tension hooks adjacent the end of the thrust bar, whereby both are supported close 95 to the rail upon actuation of said moving means.

10. In a rail drilling apparatus, in combination, a pair of relatively movable frame members provided with rail holding abutments, moving means carried by one of said frame members for moving it relatively to the other thereof, operating means connecting said moving means with the other of said frame members, and means for connecting said operating and moving means, said frames being constructed to permit disconnection and drawing apart thereof upon removal of said connecting means.

11. In a rail drilling apparatus, in combination, a pair of frame members provided adjacent one end with rail holding abutments and slidable supporting means whereby the frame members are relatively movable and at the other end with slidable supporting means, an operating lever pivoted to one of said frame members, and a toggle link pivoted to the other of said frame members and to said lever.

12. In a rail drilling apparatus, in combination, a pair of relatively movable frame members provided adjacent one end with rail holding abutments and slidable supporting means whereby the frame members are relatively movable, one of said members being provided at the opposite end with a fixed abutment, an operating lever pivoted to one of said frame members and a toggle link pivoted to the other of said frame members and the said lever, said lever being pro- 130

vided with an abutment coöperating with said last mentioned abutment and said toggle link, whereby said first mentioned abutments are restrained from separation.

5 13. An apparatus of the character described comprising, in combination, a unitary cast supporting frame, a tool carried by the frame, a plurality of driving members supported by the frame for imparting motion 10 to said tool, a shaft carrying a plurality of driving members having operative connection to said first mentioned driving members supported by said frame, a thrust member on said frame adapted to engage the rail, a 15 second frame provided with a tension member coöperating therewith and slidably supporting the first mentioned frame, and means for moving the first mentioned frame relatively to the other whereby a rail may 20 be gripped between the tension and thrust members.

14. An apparatus of the character described comprising, in combination, a supporting frame, a tool carried by the frame, 25 a plurality of driving members supported by the frame, for imparting motion to said tool, a shaft carrying a plurality of driving members having operative connection to said first mentioned driving members supported 30 by said frame, a thrust member carried by the frame adapted to engage the rail, a second frame provided with a tension member coöperating therewith, and means for moving the first mentioned frame relatively to 35 the other whereby a rail may be gripped between the tension and thrust members.

15. In a device of the character described, in combination, a drill stock provided with a thread a nut having threaded connection 40 with said stock, a bushing having slidable and non-rotatable engagement with said stock, a frame for supporting said nut and bushing, means for rotating said nut and bushing, and a sleeve to protect the thread 45 of the drill stock between said nut and bushing.

16. In a device of the character described, in combination, a drill stock provided with a thread a nut having threaded connection

with said stock, a bushing having slidable 50 and non-rotatable engagement with said stock, a frame for supporting said nut and bushing, means for rotating said nut and bushing and a sleeve 69' protecting the extended portion of said stock. 55

17. In a device of the character described, in combination, a drill stock, means for revolving the stock, means for feeding the stock, driving means for said feeding and revolving means, and spring held means 60 thereon whereby the driving means may be connected with or disconnected from said revolving means, so that the revolving means and the feeding means may be operated simultaneously or the feeding means actuated 65 alone.

18. In a device of the character described, in combination, a drill stock provided with a thread, a nut having threaded connection 70 with said stock, a bushing having slidable and non-rotatable engagement with said stock, a frame for supporting said nut and bushing, gearing members for rotating said nut and bushing, a driving shaft, gearing members on said shaft for driving said first 75 mentioned gearing members, one of said last mentioned gearing members being loose on said shaft and spring held means acting on said loose gearing member for causing it to rotate with said shaft. 80

19. In a rail drilling apparatus, in combination, a pair of rail holding abutments mounted for slidable movement relatively to each other, a take-up device for varying the distance between opposing abutments, toggle 85 means for causing said abutments to approach to grip a rail therebetween, and means for locking said abutments against relative movement.

In testimony whereof we have hereunto 90 signed our names in the presence of the two subscribed witnesses.
